United States Patent Office

Des. 179,648
Patented Feb. 5, 1957

179,648

BOTTLE CARRIER

Leroy E. Larsen, Old Greenwich, Conn., assignor to The Coca-Cola Company, New York, N. Y., a corporation of Delaware

Application February 7, 1956, Serial No. 40,068

Term of patent 14 years

(Cl. D58—5)

Fig. 1 is a perspective view of a bottle carrier embodying my new design; and

Fig. 2 is a perspective view of the opposite side thereof. The drawing is shaded to indicate contrast in color.

I claim:

The ornamental design for a bottle carrier, as shown and described.
